(57) CLAIM

The ornamental design for a fitness glove, as shown and described.

DESCRIPTION

FIG. 1 is a front perspective view of a fitness glove showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is an enlarged portion taken through line 8-8 of FIG. 2;

FIG. 9 is a front plan view showing an opening of the fitness glove in an expanded position;

FIG. 10 is a front elevation view of an environmental in-use example of the fitness glove with the opening in another expanded position; and,

FIG. 11 is an enlarged view of a portion of FIG. 10. The broken-line showing of portions of a hand and arm in FIGS. 10 and 11 show environmental features that form no part of the claimed design. The remaining larger broken lines of even length in FIGS. 10-11, as well as the larger broken lines of even length in the remaining figures depict portions of the fitness glove that form no part of the claimed design. The smaller broken lines of even length depict stitching and form part of the claimed design. The broken lines of uneven length are boundary lines that form no part of the claimed design. The broken line cross-hatching shown in the cross-section of FIG. 8 forms no part of the claimed design.
